UNITED STATES PATENT OFFICE.

WILLIAM H. BOUTELL, OF ROCHESTER, NEW YORK. ASSIGNOR TO BOUTELL MANUFACTURING COMPANY, OF ROCHESTER, NEW YORK, A CORPORATION OF NEW YORK.

FRUIT OR VEGETABLE SLICING MACHINE.

1,102,467.

Specification of Letters Patent.

Patented July 7, 1914.

Application filed July 13, 1907. Serial No. 383,603.

To all whom it may concern:

Be it known that I, WILLIAM H. BOUTELL, of Rochester, in the county of Monroe and State of New York, have invented certain new and useful Improvements in Fruit or Vegetable Slicing Machines; and I do hereby declare the following to be a full, clear, and exact description of the same, reference being had to the accompanying drawings, forming a part of this specification, and to the reference numerals marked thereon.

This invention relates to fruit or vegetable slicing machines of the type in which the articles are fed by a suitable mechanism to slicing devices, and it has for its object to provide a feeding mechanism constructed to limit the feed to a single article, whereby the clogging of the slicing mechanism is prevented, and to provide certain improvements in the slicing mechanism which will facilitate the removal of the knives and prevent waste of the sliced material.

To these and other ends the invention consists in certain improvements and combinations of parts all as will be hereinafter more fully described, the novel features being pointed out in the claims at the end of the specification.

In the drawings: Figure 1 is a top view of a machine constructed in accordance with my invention; Fig. 2 is a side view; Fig. 3 is a vertical longitudinal section; Fig. 4 is a vertical transverse section through the hopper; Fig. 5 is a detail view showing the manner in which the articles in the feeder are agitated.

The embodiment of the invention herein shown employs a suitable frame A for supporting a slicing or cutting mechanism which in this instance comprises a table or support 1 having thereon an annular guard 2 and a roughened surface in the form of a series of over-lapping plates 1^a serving to agitate the articles and cause those such as apples to present their flat ends to cutters 3 of any suitable form arranged in an arcuate series within the guard and carried by a cutter carrying frame 3^a which is removably secured by thumb nuts 3^b and bolts 3^c to the under side of the table. Adapted to turn above the table with a vertical shaft 4 journaled in the frame A is a carrier frame which comprises an annular ring 5 sup-

ported within the outer guard from shaft 4 by spiders 6, serving as an inner guard for the articles on the table and having a plurality of pocket shaped carriers 7 extending radially therefrom, and adapted to carry to the knives fruit, vegetables or the like delivered on the support 1 through chute 8 arranged on the frame A and forming part of a feeding mechanism to be described, a shield 9 above the carriers acting to prevent the articles passing directly from the chute to the knives.

The articles are fed singly to the chute 8 by means of a vertically arranged feeder in the form of an endless series of carriers 10 which pass the chute 8 upon their upward travel 70 and in this instance project from one edge of a flexible belt 11 passing about a small pulley 12 and a large pulley 13. The small pulley preferably is supported on a stub shaft 14 which extends from the side of the frame and is supported at one end only by a bracket arm 15 projecting upwardly from the horizontal cross piece 17 which is secured to frame A and also carries a vertical bearing for the shaft 4. The larger pulley 80 13 is journaled on a shaft 16 which also extends from the frame and is secured at one end only to a vertically adjustable bracket 18 mounted on the lower portion of the frame and serving by its adjustment to 85 tighten or loosen the belt.

The belt is driven by a gear 19 on the small pulley 12, meshing with a small gear 20 on a horizontal drive shaft 21 which is journaled at one end in bracket arm 15 and 90 at its other end in a vertically extending bracket 22 on horizontal cross piece 17. The drive shaft 21 also actuates the slicing mechanism and for this purpose is geared to the shaft 4 which carries a larger crown 95 gear 23 meshing with a small bevel pinion 24 on the drive shaft.

The endless feeder takes the articles from a suitable hopper which preferably comprises an end board 25, lying substantially 100 in the plane of the outer edge of the belt and cut away so as to conform to the outline of the latter; and a chute portion 26 connected by tie bolts 27 to the end board. Devices in the form of bolts 28^a work in vertical slots 105 in the end board and permit the vertical adjustment of the hopper so that it may maintain a proper relation with the endless

feeder; and segmental pieces 13^a close the pulley 13 to prevent the passage of articles from the hopper through the pulley.

To the end that the feeder will not engage the articles in the hopper upon its downward movement a guard 28 covers that portion of the feeder that is moving downwardly within the hopper. In this manner the articles are caused to be engaged only after the feeder has started on its upward movement and are carried upwardly by the carriers 10 which for this purpose are inclined relatively to the end board 25 to form therewith pockets preventing the articles being dropped until the upper end of the board is reached when they roll into chute 8. At the feeding point I provide means to engage the articles to cause them to leave the carriers and in this instance the carriers 10 are provided with openings or slots 29 through which works a finger 30 preferably supported on the end board on one side of the carriers, extending outwardly therefrom, thence laterally in front of the carriers and finally upwardly and inwardly toward the end board in a position to pass through the slots 29 when the carriers reach the chute 8.

The number of articles entering each carrier at one time is limited to one, by means of a rearwardly extending fin, or arm 31, at the outer end of each carrier and of such a length that while one article may enter a carrier in the rear of the one carrying the arm, others will be barred if seeking to enter at the same time. Even with these barriers I have found that at times more than one article will be clamped between two carriers, and to prevent this, I provide on that portion of the end board over which the articles pass in being fed to the slicing mechanism an agitator preferably a roughened surface in the form of overlapping plates 131, which agitate the articles on the carriers and cause any surplus to fall therefrom, the hopper being formed with an enlargement 32 on its adjacent side to catch those falling and conduct them to a position to be again caught by the feeder.

Owing to the fact that the belt is flexible, the weight of the carriers 10 with the fruit

thereon, is, under ordinary circumstances, sufficient to cause the belt to bend and tilt the carriers to prematurely discharge their contents, and to prevent this I employ a support 33 in the form of a bar bearing upon the inner surface of the working portion of the belt of the feeder to overcome its sagging, and means permitting the adjustment of the bar consisting preferably of a slotted bracket 34 secured to the frame by bolts 35 whereby the bar may be shifted to vary the pressure on the belt.

From the foregoing, it will be noted that I have provided a simple and inexpensive machine, which expeditiously conveys the articles to the slicing mechanism without clogging the latter, or injuring the articles, and in which waste of the cut articles is prevented.

I claim as my invention.

1. The combination with a table, of an elevating feeder arranged at one side of the table and embodying an endless series of carriers, each having a slot, and a finger for directing the articles to the table when the carriers shall have reached the top of the elevating feeder, the finger being arranged at one side of the feeder in proximity to the feeding point and projecting upwardly, thence laterally over the path of the carriers, and finally upwardly and inwardly so as to pass through the slots.

2. The combination with a table, and a hopper, of a feeder for conveying articles from the hopper to the table embodying an endless series of carriers each having a rearwardly extending arm projecting far enough toward the next adjacent carrier following the arm to prevent the entrance of more than one article to the same.

3. The combination with a table and a hopper having an upright end board, of an endless feeder for the table having carriers thereon, and a plurality of overlapping blades on the end board over which the carriers pass in moving upwardly toward the table.

WILLIAM H. BOUTELL.
